TENSION DEVICE

Harold Wood Hitchcock, Apponaug, R. I., assignor
to Universal Winding Company, Boston, Mass.,
a corporation of Massachusetts

Application May 5, 1939, Serial No. 272,033

10 Claims. (Cl. 242—150)

This application is a continuation in part of my prior applications for United States Letters Patent, Serial No. 224,386, filed August 11, 1938, and Serial No. 251,816, filed January 19, 1939, now Patent No. 2,207,863.

The present invention relates to improvements in devices for tensioning strand materials such as yarn, thread and the like during their delivery to winding machines or in other transfer processes.

In the following specification and claims the term "yarn" is employed in a general sense to apply to all kinds of strand materials, either textile or otherwise, and the designation "package" is intended to indicate the product of the winding machine whatever its form.

One object of the invention is to provide a differential tension-device adapted to operate automatically to maintain a uniform tension on the yarn during the winding or other operation.

Another object of the invention is to provide a tension-device comprising opposed disks with means for regulating the pressure on the disks to vary the tension applied to the strand in accordance with the rate of its linear travel.

Another object of the invention is to provide in a device of the type indicated means for positively controlling the tension applied to the yarn without the use of weights or other elements liable to cause vibration or chatter of the tension-elements.

Another object of the invention is to provide a tension-device of the type indicated in which the tension-members may be readily separated for inspection and cleaning purposes.

Another object of the invention is to provide in a tension-device of the type indicated pressure means for normally urging the tension-members into cooperative relationship to act on the strand and adapted to permit manual separation of the members, said means being automatically operable to restore the tension-members to cooperative relationship.

Another object of the invention is to provide a tension-device of simple structure and arrangement adapted for economical manufacture and proof against derangement and excessive wear during extended periods of operation.

Further objects of the improvement are set forth in the following specification which describes one preferred embodiment of the invention and a modified form thereof as illustrated by the accompanying drawings. In the drawings:

Fig. 1 is a side elevation of a conventional type of winding machine incorporating a tension-de-

vice for applying tension to the strand of yarn being wound and illustrating the improved controlling means for progressively relieving the applied tension as the linear speed of the yarn increases during the winding operation;

Fig. 2 is an enlarged part-sectional side elevation of the tension-device and the controlling means therefor, showing the position assumed by the parts at the commencement of the winding operation;

Fig. 3 is a view similar to Fig. 2 showing the relationship of the parts at a later stage in the winding operation;

Fig. 4 is a plan view of the tension-device and its controlling means;

Fig. 5 is a fragmentary plan view of the tension-device and the pressure-means therefor showing the tension-disks separated to permit inspection and cleaning;

Fig. 6 is a side view of the same with the parts shown partly in section;

Fig. 7 is a vertical sectional view of the tension-device shown with a modified form of pressure means and incorporating the present improvement; and

Fig. 8 is an end view of the tension-device illustrated in Fig. 7.

The present invention is concerned particularly with tension-devices for winding machines in which the winding-spindle is rotated at a constant speed so that during the winding of a package thereon the rate of linear travel of the yarn progressively increases with the increase in circumference of the wound mass. It is well known to those skilled in the art that in winding on machines of this type as the winding progresses and the package increases in circumference the yarn must feed thereto at a progressively accelerated rate, that is, with an increasing linear speed and, therefore, unless controlled, the tension on the running yarn will be augmented from this cause. It has heretofore been proposed to provide means for gradually relieving or reducing the applied tension on the yarn during the growth of the package and the present invention is distinguished from such known devices

in that it provides a positive control of the tension-members rather than through the use of adjustable weights and like unstable elements liable to vibration.

The invention is herein shown as applied to use on a winding machine of conventional type wherein the package is wound on a positively driven winding-spindle and the yarn traversed longitudinally thereof by means of a reciprocating

ing thread-guide. The present tension-controlling means is similar in construction to that illustrated and described in my prior applications before mentioned, but in addition the present improvement provides for manual release of the pressure means and separation of the tension-members for inspection and cleaning. It is to be understood, however, that the invention may be used for controlling the operation of tension-devices of other types wherein the tension-elements are progressively separated, one from the other, or the pressure of one against the other relieved during the winding or like operation.

Fig. 1 of the drawings illustrates a well-known type of winding machine comprising a main frame 2 having upper bearings for a rotary winding spindle 3 and lower bearings for a cam-shaft 4. Cylindrical or conical packages may be wound on the spindle 3 by traversing the yarn longitudinally thereof through the means of a reciprocating thread-guide 5 which is supported on a swinging traverse-frame 6. The thread-guide 5 is connected to a traverse-rod 7 slidable in grooved bearings in the traverse-frame 6 and arranged to be reciprocated by a helical cam, not herein shown, which is rotated by the cam-shaft 4. The traverse-frame 6 is pivoted on the cam-shaft 4 to adapt the thread-guide 5 carried thereby to move outwardly away from the winding-spindle 3 as the package is built up thereon. To counterbalance the traverse-frame 6 and maintain the thread-guide 5 bearing against the package during the progress of the winding the traverse-frame is preferably provided with a weighted arm 8 depending therefrom in the manner of a pendulum.

As a further means for resisting the pressure of the package against the thread-guide 5 which tends to swing the traverse-frame 6 away from the spindle 3, a differential pressure-device is employed. The differential pressure-means comprises a lever 9 pivoted on a stud 10 screwed into a boss on the side of a curved arm 28 which supports a tension-bracket 30, to be described later. The tension-bracket 30 is fastened to the side of the frame 2 at 31. A weight 11 slidably mounted on the lever 9 is adjustable therealong to vary its operative pressure on the traverse-frame 6. As shown in Fig. 4, the lever 9 is of bifurcated form having two arms with a hub 12 therebetween for pivoting it on the stud 10. A U-shaped link 13 has one end hooked through alined holes in the sides of the lever 9 and headed over to retain it in place; while its opposite bent end is hooked into one of a series of slots 14 formed in the side of a sheet-metal bracket 15 adjustably mounted on the weighted arm 8 of the traverse-frame 6. The lever 9 and weighted arm 8 act to resist the outward swinging movement of the traverse-frame 6 to maintain the thread-guide 5 bearing against the package being wound with the required pressure. As the winding progresses and the traverse-frame 6 swings in a clockwise direction, as viewed in Fig. 1, the lever 9 is swung upwardly by means of the link 13 to relieve the pressure tending to resist the movement of the thread-guide away from the winding-spindle.

The tension-device 20 is shown and described in detail in my prior application, Serial No. 224,386, and is therefore referred to herein only briefly as related to the operation of the pressure means. Suffice it to state that a pair of concavo-convex disks 21 and 22 are rotatably mounted on a rod or spindle 23 slidable in the

bore of a sleeve 24. The sleeve 24 has a knurled head 25 and its main portion is externally threaded to engage the interiorly-threaded bore of a hub or boss 27 formed integral with the tension-bracket 30. The sleeve 24 may be adjusted longitudinally in the boss 27 and is held in adjusted position by means of a knurled lock-nut 29 screwed onto the sleeve and set up against the side of the boss. The tension-disks 21 and 10 22 are of saucer shape, being preferably constructed of sheet-metal with their opposed portions having flat faces adapted to bear against the strand s drawing therebetween.

The means for applying pressure to the disks 21 and 22 to force them toward each other to adapt them to bear against the strand s may consist in a flexible diaphragm 35 for each disk constructed from suitable resilient material such as rubber, fiber or the like. The diaphragms 35 are of disk-form as shown in Fig. 3, having substantially the same outside diameter as the tension-disks 21 and 22 to adapt them to bear against the rims of the latter in the manner illustrated in Fig. 2. The diaphragms 35 are formed with axial holes for supporting them on the central spindle 23 and pressure is applied to the diaphragms adjacent their centers to cause them to yieldingly press against the outer rims of the disks 21 and 22.

The tension-device illustrated in Figs. 7 and 8 differs from that described above only in the form of the pressure means employed therewith. In this case the pressure-elements are in the form of spider-like springs 36 slidably mounted on the spindle 23 with the ends of their radial arms bearing against the outer rims of the tension-disks 21 and 22.

In either case, the diaphragms 35, or the spring-elements 36, are forced toward each other 40 under pressure applied thereto to urge the tension-disks 21 and 22 toward each other to apply resistance to the passage of the yarn drawing therebetween. As herein shown, a preferred form of construction of the pressure means comprises the spindle or plunger-rod 23 on which the tension-disks 21 and 22 are mounted and which is slidable in the sleeve 24. The inner diaphragm 35 has its central portion abutting the end of the sleeve 24, while the central portion of the outer diaphragm 35 is engaged by a washer or other abutment 37 secured to the outer extremity of the rod or spindle 23 by means of a screw 38. It will thus be observed that when the rod or spindle 23 is slid to the left, as viewed in Fig. 2, the abutment 37 will bear against the central portion of the outer diaphragm 35 to cause pressure on both diaphragms whereof to adapt them to yieldingly press against the rims of the two disks 21 and 22. As the pressure of 55 the abutment 37 is increased the diaphragms will be flexed to cause them to be bowed inwardly toward each other to a slight extent.

With the form of tension-device shown in Figs. 7 and 8 the spring-elements 36 are flexed 60 in the same manner to cause them to be bowed inwardly toward each other to a slight extent. The inner spring 36 may be held against rotation by a screw 40 in the bracket 30 engaging the side of one of the radial arms of the spring. Rotation of the outer spring 36 is prevented by an arm 41 formed integral with and extending laterally from the abutment or washer 39 into engagement with the side of an arm of the spring.

The strand s leads upwardly from a suitable

source of supply, not herein shown, passes through a pigtail guide 44 supported by the bracket 38, and across a rod 45 forming one element of a slab-catcher 46 mounted at the upper end of the bracket. From the guiding rod 45 the strand s leads across a wire-ball 47 carried by the traverse-frame 6 and thence through a groove in the thread-guide 5 to the package being wound.

A bifurcated tension-lever 50 has a hub-portion 51 mounted on the stud 10, previously referred to, with arms 52 and 53 radiating therefrom and connected at their ends by a cross-strut 54, see Fig. 4. The hub 51 is held axially in abutting relation to the hub of the lever 8 by means of a washer 55 and screw 56. The arms 52 and 53 of the lever 50 are provided with aligned holes for receiving the body-portion of an adjusting stud 59. As shown in Figs. 3 and 4, the adjusting stud 59 has an eccentric disk-like portion 60 at its forward end with its side abutting the outer face of the arm 52 while its shank-portion extends beyond the arm 53 with its end provided with a threaded bore. An enlarged head 61 formed at the outer end of the stud 59 is slotted to receive a screw-driver to facilitate turning the stud when adjusting the position of its eccentric portion 60 for a purpose to be explained later. A link 65 has an eye or loop at one end enclosing the end of the stud 59 and held in place abutting the side of the lever-arm 53 by means of a headed screw 66.

The opposite end 67 of the link 65 is pivotally connected to a sheet-metal bracket 68 by means of a stud 69 passing through one of a series of holes 70 in the bracket and held in place by a nut 71, see Fig. 4. The bracket 68 is pivoted on a stud 72 held in the bracket 15, previously described as fastened to the side of the traverse-frame arm 8 and forming part of the differential pressure means common to winding machines of the type herein illustrated. The bracket 68 is provided with an arcuate slot 73 through which passes a screw 74 screwed into a threaded hole in the bracket 15. By loosening the screw 74 the smaller bracket 68 may be adjusted about the stud 72 and thereafter secured in position by tightening the screw. It will be apparent that during the winding operation the swinging motion of the traverse-frame 6 will rock the weighted arm 8 in a clockwise direction, as viewed in Fig. 1, and through its connection by the link 65 with the lever 50 the latter will be rocked about its pivot 18 in a counterclockwise direction.

The forward arm 52 of the lever 50 is longer than its rearward arm 53, as shown in Fig. 4, and is provided at its extremity with a threaded hole for receiving the reduced threaded end of a stud 76. Pivoted on the larger shank-portion 77 of the stud 76 is a sheet-metal lever 80 provided with a longitudinal slot 81, see Fig. 3, with an enlargement or opening 85 at its end arranged with its sides embracing the periphery of the eccentric portion 60 of the adjusting stud 59. The narrower portion of the slot 81 renders the upper portion of the lever 80 resilient whereby to cause the sides of the opening 85 to exert pressure on the eccentric portion 60 of the stud 59. In this way the sides of the opening 85 form jaws which engage the eccentric 60 frictionally to resist turning movement of the stud 59. The lever 80 is extended forwardly and then laterally in a portion 82 which is provided

with a hole 83 at its end for connecting it with the pressure means of the tension-device 20.

The plunger-rod or spindle 23, previously described as slidably mounted in the sleeve 24 of the tension-device 20, is slotted or bifurcated at its rearward extremity, as shown at 89 in Fig. 5, to adapt it to receive one end of a link or extension 90. A pin 91 passing through holes in the sides of the bifurcated end of the spindle 23 also passes through a longitudinal slot 92 in the link 90 to connect the latter therewith. As shown in Figs. 4 and 5, the pin 91 has a head 93 abutting the rearward side of the spindle 23 while its other end is headed over to hold it fixedly in place. The opposite end of the link 90 is pivotally connected to a stud 95 screwed into the end of the extension 82 of the lever 80. As shown in Fig. 4, the end of the link 90 surrounds the enlarged shank-portion 96 of the stud 95 between its head 97 and the side of the lever-extension 82 and the stud is held in place by a nut 98 screwed onto its end and abutting the opposite side of the extension. Adjacent this end of the link 90 is a pin 100 riveted through a hole in the link. The pins 100 and 91 are provided with circumferential grooves for receiving the hooked ends of a relatively stiff helical spring 102 which acts to draw the spindle 23 toward the left as viewed in Fig. 2 and normally maintains its pin 91 in engagement with the left-hand end of the slot 92 of the connecting-link 90.

A preferred form of construction of the tension-controlling device having been described in detail its method of operation is explained as follows: To prepare the machine for winding, the strand s of yarn or the like is drawn upwardly through the guide 44, threaded between the tension-disks 21 and 22, and thence led across the guide-rod 45 and ball 47. The strand is then passed through the slot in the thread-guide 5 and its end attached to the tube t or other yarn-receiver mounted on the spindle 3; the traverse-frame 6 being then moved into position to place the thread-guide against the copetube t. The tension-controlling device, including the levers 50 and 80, will then assume the position substantially as shown in Fig. 1. The tension on the strand s is initially regulated by adjusting the sleeve 24 longitudinally of the hub 27 to cause it to bear against the inner diaphragm 35 to flex both diaphragms, or spring-elements 36, as the case may be, to the required degree. It will be observed that the spindle 23 and its extension or link 90 are held in longitudinally-contracted or telescoped relationship by the tension of the relatively strong spring 102 with the pin 91 engaging the left-hand end of the slot 92 in the link as viewed in Figs. 3 and 4. The adjustment of the sleeve 24 will tend to flex the diaphragms 35, or springs 36, to bear against the rims of the tension-disks 21 and 22 and thus the initial tension applied to the strand s at the start of the winding is regulated in accordance with requirements.

The controlling device is further adjusted to regulate the extent of sliding movement imparted to the plunger-rod or spindle 23 by the traverse-frame 6 during the winding of a package, and thereby the extent to which the applied tension is relieved. Turning the adjusting stud 59 by means of a screw-driver causes its eccentric portion 60 to swing the lever 80 about its pivot-stud 76. The adjusting stud 59 may be turned in a clockwise direction, as viewed in Fig. 2, to

adjust the connected end of the link 90 into eccentric relation to the axis of the pivot-stud 10. With the lever 80 adjusted in position with the stud 96 in eccentric relation to the axis of the pivot-stud 10 the rocking movement of the levers 50 and 80 during the winding operation will cause the end of the connecting-link 90 to swing in an arc concentric with the axis of the stud 10 in the manner of a crank-pin; and since the pin 91 of the spindle 23 is held in engagement with the end of the slot 92 by the spring 102 the spindle will be moved bodily toward the right to gradually relieve the pressure of the diaphragms 35 against the rims of the tension-disks 21 and 22.

By the above-explained method of operation of the control-device the pressure of the two diaphragms on the tension-disks 21 and 22 is relieved so that the pressure of the disks on the strand's drawing therebetween is correspondingly diminished. It will be understood that this relief of the pressure on the diaphragms and the corresponding reduction in the pressure of the tension-disks on the strand is effected gradually and continuously from start to finish of the winding of each package and in direct proportion to the increase in linear speed or rate of draft of the strand as the package grows in size. In fine, as the speed of draft of the yarn increases due to the growing diameter of the package being wound the applied tension on the yarn is gradually relieved so that the ultimate tension remains substantially constant or uniform throughout the winding.

During the winding operation the weighted arm 6 acts through the link 13 to swing the weighted lever-arm 9 upwardly to gradually diminish the active pressure tending to resist movement of the thread-guide 5 away from the winding spindle 3. It will be noted that the arms 6 and 50 are independently pivoted on the common stud 10 and since their pivotal movement is controlled by separate links 13 and 65 the rocking movement of either arm will not affect the movement of the other arm.

It has been explained that the pin 91 in the end of the spindle 23 is normally held in engagement with the left-hand end of the slot 92 in the link 90 by means of the spring 102 to maintain the tension-disks 21 and 22 in cooperative relationship with the diaphragms 35, or springs 36, as the case may be, flexed to the required degree. It is sometimes desirable to open the tension-device, that is by separating the disks 21 and 22 so that their yarn-engaging surfaces may be inspected and cleaned of lint, specks or the like; or to clear the device of any loose yarn that may have become entangled around the spindle 23. When it is desired to separate the tension-disks the operator merely grasps the outer disks 22, or the abutment 37 on the spindle 23, and draws the latter outwardly or toward the right in the manner indicated in Figs. 5 and 6. During this longitudinal movement of the spindle 23 its pin 91 will slide in the slot 92 of the link 90 and extend the spring 102 until finally the pin brings up against the right-hand end of the slot to prevent further movement of the spindle in this direction. With the disks 21 and 22 separated their yarn-engaging surfaces and the spindle 23 may be readily cleaned, after which the spindle 23 is released and permitted to return to initial position under the action of the spring 102. Return movement of the spindle 23 is limited by the re-engagement of its pin 91

with the left-hand end of the slot 92 in the link 90 and thus the tension-disks and diaphragms 35 automatically restored to their cooperative relationship. It is to be particularly noted that the separation of the tension-disks in the manner as explained above does not disturb the adjustment of the tension-controlling elements. Furthermore, with the parts in their normal position the pin 91 is held against the end of the slot 92 by the action of the relatively stiff spring 102 so that positive operation of the device without vibration is secured.

It will be observed from the foregoing that the present invention provides a particularly simple yet ingenious means for positively and accurately controlling the pressure on the tension-members during the winding of a package whereby to relieve the tension applied to the yarn as the linear speed of the latter increases. In this way the device operates automatically to maintain a substantially constant and uniform tension on the yarn from start to finish of the package.

The tension-controlling device is operated directly from the winding mechanism in direct proportion to the growth of the package being wound without the use of weights or other unstable elements liable to cause vibration or chatter of the tension-elements and result in uneven tension being applied to the yarn. The improved tension-controlling means may be quickly and accurately adjusted to effect a range of action necessary to properly relieve the tension during the winding or like operation.

As a particular feature of improvement in the present invention the tension-controlling device is so constructed that the tension-elements may be separated one from the other when it is desired to inspect or clean their yarn-engaging surfaces or the spindle on which they are mounted, while being automatically restored to cooperative relationship after the separation.

While the invention is herein shown and described as embodied in a preferred form of construction, it will be understood that modifications may be made in the structure and arrangement of the parts of the device and in the method of applying it to use without departing from the spirit or scope of the invention. Therefore, without limiting myself in this respect, I claim:

1. A tension-device comprising a member adapted to bear against a strand of yarn or the like to apply resistance to its draft, resilient means for forcing said member against the strand, a lever, a two-part spindle actuated by said lever to maintain the resilient means under compression, and a second resilient means arranged between the parts of the spindle to permit extension of the latter to release it from the first resilient means.

2. A tension-device comprising a two-part spindle, a tension-disk supported coaxially of said spindle, resilient means acting against the tension-disk, means on the spindle acting against the resilient means to maintain the latter under compression, a lever for sliding the spindle to relieve the compression of the resilient means, means for actuating said lever, and a spring between the parts of the spindle adapted to permit manual extension of the spindle to remove the compression means from the resilient means.

3. A tension-device comprising a slidably spindle, a pair of tension-disks mounted coaxially of said spindle to adapt them to bear against a strand of yarn feeding therebetween, resilient

means acting against said tension-disks to cause them to press against the strand, means carried by the spindle for compressing the resilient means, a link slidable longitudinally of the spindle, a lever for moving said link to slide the spindle to relieve the compression of the resilient means, and a spring for maintaining said link and spindle interconnected for sliding the latter while permitting the spindle to be slid manually without moving the link to allow separation of the tension-disks.

4. A tension-device comprising a slidable spindle, a pair of tension-disks supported coaxially of said spindle, resilient means acting against said tension-disks to cause them to press against a yarn feeding therebetween, an abutment on the spindle acting against the resilient means to maintain the latter under compression, an extension telescopically connected to the spindle, a spring acting between the extension and the spindle to maintain them normally in contracted relationship, and means acting on the extension to slide the spindle to relieve the pressure of the abutment against the resilient means.

5. A tension-device comprising a slidable spindle, a pair of tension-disks arranged coaxially of said spindle, resilient means acting against the tension-disks to adapt them to press against a strand drawing therebetween, an abutment on the spindle for maintaining the resilient means under compression, an extension slidable axially of the spindle, means to limit the sliding movement of the extension with respect to the spindle, a spring for normally maintaining said spindle and extension in axially-contracted relationship, and means acting on the spindle-extension to slide the spindle to gradually relieve the pressure of the compression means against the resilient means.

6. A tension-device comprising a slidable spindle, a pair of tension-disks arranged concentrically of said spindle, resilient means acting against the tension-disks to cause them to press against a strand drawing therebetween, an abutment on the spindle for maintaining the resilient means under compression, an extension slidable axially of the spindle, said extension and spindle being joined by a pin-and-slot connection, and a spring for normally maintaining said spindle and extension in axially-contracted relationship with the pin at the end of the slot.

7. A tension-device comprising a support, a

sleeve threaded through an opening in the support, a spindle slidable in said sleeve, a pair of opposed tension-disks mounted on said spindle and having peripheral rims, resilient means bearing against the rims of the tension-disks, and an abutment on the spindle bearing against said resilient means, said sleeve and abutment acting to maintain the resilient means under compression.

10 8. A tension-device comprising a tension-member adapted to bear against a running yarn to cause resistance to its draft, a two-part extensible spindle for supporting said tension-member, resilient pressure means acting against the tension-member, means on the spindle acting against the pressure means to maintain the latter under compression, one of said spindle parts being manually slidable with respect to the other part to release the means on the spindle from the pressure means, and resilient means acting between the spindle parts to yieldingly hold them in contracted relationship to cause the means on the spindle to act on the pressure means.

9. A tension-device comprising a pair of tension-members adapted to bear against a strand of yarn or the like feeding therebetween, resilient pressure means acting against said tension-members to press them against the strand, a two-part extensible spindle for supporting said tension-members, an abutment on the spindle acting on the pressure means to maintain the latter under compression, one of said spindle parts being axially movable with respect to the other part to relieve the pressure of the abutment on the pressure means, and means for yieldingly maintaining the spindle parts in contracted relationship to cause the abutment to compress the pressure means.

10 40 A tension-device comprising a tension-member adapted to bear against a strand of yarn or the like to apply resistance to its draft, resilient means for forcing said member against the strand, a two-part spindle acting on the resilient means to maintain the latter under compression, means acting to slide the spindle to relieve the pressure of the resilient means on the tension-member, and a second resilient means arranged between the parts of the spindle to permit extension of the latter to release it from the first-mentioned resilient means.

HAROLD WOOD HITCHCOCK.
